ROBERT MONSCHEIN, OF CLEVELAND, OHIO, ASSIGNOR TO THE NATIONAL CITY BANK, OF CLEVELAND, OHIO, EXECUTORS OF MORRIS H. GLAUBER, DECEASED, OPERATING AS GLAUBER BRASS MANUFACTURING CO.

FAUCET

Application filed December 12, 1929. Serial No. 413,539.

The present invention relates to an improvement in faucets, and the object in general is to provide a combination faucet having a swinging spout and a soap dish constructed and related substantially as hereinafter shown and described and more concisely pointed out in the claims. Combination faucets having depending spouts and superposed soap dishes are known, but in the present 10 faucet both the spout and soap dish are mounted centrally above the body of the faucet in a simple and effective way, and the soap dish is supported at a substantial height above the faucet handles and the 15 swinging spout is also placed in its entirety at a higher elevation than the faucet body and free to swing without coming into contact with any vessel or object beneath the faucet.

20 In the accompanying drawings, Fig. 1 is a front elevation of a combination faucet embodying the improvement, and Fig. 2 is a sectional view thereof on line 2—2 of Fig. 1. Fig. 3 is a cross section of the soap dish 25 mounting on line 3—3 of Fig. 2. Fig. 4 is a sectional view of the faucet body with the spout and dish removed and the supporting member for said parts affixed to the body. Fig. 5 is a sectional view and elevation 30 responding in part to Fig. 2, but showing the soap dish removed. Fig. 6 is a cross section of the spout on line 6—6 of Fig. 2. Fig. 7 is an enlarged sectional view of a modified form of rotatable union for the spout.

35 The faucet comprises an elongated hollow body 2 having hot and cold water branches and valves 3 and 4 respectively, at its opposite ends. The valves and branches may be variously constructed and arranged 40 according to common practices, but body 2 is preferably provided at its middle with a bulbous enlargement 5 having an upwardly extending outlet branch or neck 6 which is smoothly finished internally and screw-threaded externally. An integral lug 7 extends inwardly from one side wall of the bulbous enlargement 5, and this lug has a screw-threaded opening 8 in line with the axis of neck 6 to receive and support the screw-threaded lower end of a shaft or cylindrical

member 9. The upper end 10 of shaft 9 is square, a section 11 adjoining this end is round, and the relatively longer portion 12 of the shaft is triangular in cross section. The triangular portion 12 extends through 55 the tubular supporting extension 14 of a delivery spout 15 when the spout is mounted upon and secured to the neck 6 of body 2, by a union nut 16. The round part 11 on shaft 9 extends through a tubular nut 17 60 screwed into the upper end of a round enlargement 18 of the spout, thereby providing a lateral support for the spout and permitting the spout to rotate thereon. The tubular extension 14 of the spout is reduced in diameter to provide an annular shoulder 19 adapted to abut the upper end of the union nut 16, and the lower end of the reduced extension 14 is screw-threaded to permit a screw-threaded ring or washer 20 to be secured 65 thereto.

A smoothly finished side-thrust collar 21 70 is sleeved upon extension 14 above the screw-ring 20, and this collar centers the supporting extension 14 of the spout within the outlet branch or neck 6 of body 2, and permits the spout to swing in respect thereto. A packing ring or suitable packing material 22 75 is clamped between the upper edge of neck 6 and union nut 16, thereby securing the spout rotatably in place upon body 2 with fluid-tight sealing effect at the joint.

The square upper end 10 of rigid shaft 9 projects upwardly a short distance above the bearing nut 17 in the top of the spout to permit a soap dish 24 to be secured thereto. For that purpose the soap dish is provided at its bottom with an inset ferrule or socket 25 having longitudinally serrated or grooved inner walls 26 adapted to sleeve over the angular corners of the squared end 10 of shaft 9. In that way the dish may be locked against rotatable movement on the shaft and also squared or aligned with body 2 when first placed thereon.

95 The spout is thereby supported between the dish and the faucet body and free to swing in respect to both and also in such an elevated position that the body may be mounted much lower in a sink than other faucets and still be 100

free to swing in the sink without striking a vessel placed underneath the faucet.

A slightly modified form of the invention is shown in Fig. 7, wherein the supporting branch or extension 14 for the spout is made relatively longer and provided with a smoothly finished reduced extremity 28 adapted to engage and rotate within an opening in a cross wall 30 in body 2. A longer 10 rotatable bearing and firmer support for the spout is thereby provided, but the structure is otherwise substantially the same as hereinbefore described.

What I claim, is:

15 1. A faucet body having an internal lug and an outlet branch, an upright shaft detachably connected with said lug and extending upwardly through said branch, a dish surmounting said shaft, and a spout rotatably secured to said branch and shaft beneath said dish.

25 2. A faucet body having a vertical branch and outlet, a cylindrical member secured to said body and extending upwardly through said outlet, a spout rotatably mounted upon said branch and member, said member being reduced in size within said spout to provide a water passage, and a dish secured to the upper end of said member.

30 3. A faucet body having a vertical outlet and a rigid member extending upwardly and axially in respect to said outlet, a spout having a tubular extension rotatably mounted within said outlet and sleeved rotatably upon the upper end of said member, and a dish detachably connected to the upper end of said member.

40 4. A faucet body having a vertical outlet, a spout having a tubular intake extension projecting into said outlet, a side-thrust collar on said extension within said outlet, a supporting member fixed to said body and extending upwardly through said extension and spout, and a dish fixed to the upper end of said member.

45 5. A faucet body having a vertical outlet branch, a spout having a tubular intake extension rotatably confined within said outlet branch, a coupling nut for said spout detachably connected with said outlet branch, a rigid shaft extending upwardly from said body axially through said spout extension, and a dish surmounting said shaft and spout.

55 6. A faucet body having a vertical outlet branch, a spout having a tubular intake extension rotatably confined within said branch, a coupling nut for said spout screw-connected with said branch, a collar fixed to said branch beneath said nut, a rigid upright shaft within said branch extending through said spout, and a dish surmounting said shaft above said spout.

60 7. A faucet body having an upwardly extending outlet, a spout having a tubular intake extension extending into said outlet, a

side-thrust collar and nut on said extension, a coupling nut sleeved over said extension, an upright shaft detachably connected with said body and extending through said outlet and tubular extension, and a dish affixed detachably and adjustably to the upper end of said shaft.

In testimony whereof I affix my signature.

ROBERT MONSCHEIN.
